(57) CLAIM

The ornamental design for a “configurable massage device,” as shown and described.

DESCRIPTION

FIG. 1 is a top view of a massage device showing a first configuration of one embodiment of my new design; FIG. 2 is an identically mirrored side view thereof; FIG. 3 is a front view and is identical to the back view thereof;

FIG. 4 is a bottom view thereof;

FIG. 5 is a top perspective view thereof;

FIG. 6 is a bottom perspective view thereof;

FIG. 7 is a top view of a massage device showing a second configuration thereof;

FIG. 8 is a side view thereof;

FIG. 9 is a front view thereof;

FIG. 10 is a bottom view thereof;

FIG. 11 is a top perspective view thereof; and,

FIG. 12 is a bottom perspective view thereof.

In the drawings, the broken lines depict portions of the configurable massage device and form no part of the claimed design.
